SHOE

Arthur C. Sewall, Auburn, Maine

Application March 31, 1937, Serial No. 134,039

2 Claims. (Cl. 36—44)

My invention relates to insoles, and has among its objects the provision of an insole of improved construction particularly suitable for use in connection with shoes the uppers of which are cemented to the insole.

The invention will be best understood from the following description when read in the light of the accompanying drawing, the scope of which invention will be more particularly pointed out in the appended claims.

In the drawing:

Figure 1 is a plan of the upper side of an insole constructed according to the invention;

Fig. 2 is a section on the line 2—2 of Fig. 1;

Fig. 3 is a plan of the upper side of a modified form of insole constructed according to the invention;

Fig. 4 is a section on the line 4—4 of Fig. 3;

Fig. 5 is a plan of the sheet from which may be cut the insoles constructed according to Figs. 1 and 2;

Fig. 6 is a section on the line 6—6 of Fig. 5;

Fig. 7 is a plan of the sheet from which may be cut the insoles constructed according to Figs. 3 and 4;

Fig. 8 is a section on the line 8—8 of Fig. 7; and

Fig. 9 is a vertical transverse section through the toe portion of a shoe according to the invention, with parts omitted.

Referring particularly to Figs. 1 and 2, the insole illustrated comprises at the upper side thereof a toe portion 1 and a heel portion 3, each of which is formed of relatively stiff material such as stiff hard fiberboard, while the shank portion 5 and ball portion 7 are formed of a single sheet of relatively flexible material such as rubber impregnated fibrous cellulose material as, for example, flannel, or bibulous paper formed of alpha cellulose fibers, impregnated with latex or rubber solution or dispersion. As shown, the adjacent edges of the heel and shank portions and toe and ball portions of the several sheets are united by overlapping skived cemented joints 9. As illustrated, the entire lower side of the insole is formed of a single sheet 11 of flexible material as, for example, the same material as that of which the shank and ball portions are formed, which sheet 11 is cemented to the sheets at the upper side of the insole.

It will be observed that the above described insole presents at the under side thereof a sheet which throughout its extent is rubber impregnated fibrous cellulose material. It has been found that the uppers 35 of shoes may be readily

cemented to such material by use of latex or rubber solution which is applied to the edges 37 of the uppers or to the edges of the insole and while the cement is wet the parts pressed together, such a construction being shown in Fig. 9. Where the insole at the toe portion thereof is formed of a single thickness of fiberboard this operation would not be possible, because leather or fabric cannot be cemented to fiberboard if the parts are applied while the latex or other rubber cement is wet, it being necessary in such situations to permit the cement to dry sufficiently to secure the requisite tackiness, and for economic reasons this is more or less impractical in the shoe factory.

Preferably the lower sheet 11 is thinner than the upper sheets of the insole to enable the joints at the upper side of the insole to be skived and secure the best possible joints between them. Commonly the minimum thickness of insoles is about 3-irons, and for such an insole the lower sheet may be 1-iron in thickness and the upper sheets each 2-irons in thickness. Applicant has found that it is impractical to form skived joints of material less than about 2-irons in thickness and obtain a smooth uniform joint. Therefore, in any event, no matter what the thickness of the insole, the upper sheets ordinarily should not be less than about 2-irons in thickness. The lower sheet however, if desired, may be very thin as, for example, the thickness of ordinary wrapping paper. Were the sheets at the upper side of the insole not skived it would be necessary to form them with abutting joints, which would necessitate extreme care in forming the edges of the sheets so that there would be no openings between them. Further, when the shoe is worn these abutting edges would tend to open and thus present a defective insole. Although forming the sheets with abutting joints is not precluded, the skived joints nevertheless present a far superior construction.

The insole constructed according to Figs. 3 and 4 is similar to that above described except that the heel portion 3 and shank portion 5 at the upper side of the insole are formed of a single sheet of stiff hard fiberboard so as to secure a stiff shank as well as heel portion. The ball portion 7 at the upper side of the insole is formed of a sheet of the above described flexible material, and the toe portion 1 of stiff hard fiberboard.

In order to secure insoles of uniform characteristics, and to effect economic savings, the insoles according to Figs. 1 and 2 may be cut from an

elongated sheet illustrated in Figs. 5 and 6. This sheet at one side comprises a central zone 13 of the above described flexible material, the width of the zone being equal to the combined lengths 5 of the shank portion 5 and ball portion 7 of the insole. At opposite sides of this zone are zones 15 of the above described stiff hard fiberboard secured thereto by skived cemented joints 17 corresponding to the joints 9 of the insole, the 10 zones 15 being of sufficient width to form material for the toe portion 1 and heel portion 3 of the insoles when the latter are cut transversely from the sheet. At the opposite side of the sheet is a sheet 19 of flexible material corresponding 15 to the sheet 11 at the lower side of the insole. The insoles may be cut transversely from this sheet along the dotted lines 21, the dies preferably being so formed as to cut a plurality of insoles at a time.

20 Similarly the insoles illustrated by Figs. 3 and 4 may be cut from the sheet illustrated by Figs. 7 and 8. This sheet comprises a central longitudinally extending zone 23 of the above described flexible material of width corresponding 25 to the length of the ball portion 7 of the insole. Secured to one side of this sheet by a skived cemented joint 25 is a sheet forming a zone 27 of stiff hard fiberboard of width slightly greater than the length of the toe portion of the insole.

20 Secured to the opposite side of the sheet 23 by a similar skived cemented joint 25 is a sheet forming a zone 29 of stiff hard fiberboard of 30 width slightly greater than the combined lengths of the shank and heel portions of the insole. At the opposite side of the sheet is cemented a sheet 31 of the above described flexible material corresponding to the sheet 11 of the insole. The

insoles according to Figs. 3 and 4 may be cut from this sheet along the dotted lines 33 in the manner above described.

In forming the sheets illustrated by Figs. 5 and 7 preferably the parts are cemented together 5 by use of rubber cement which extends over the entire surfaces of the contacting parts. This cement preferably is allowed to dry to the requisite degree of tackiness before the parts are applied. Conveniently the side of the sheet having the 10 fiberboard zones is first formed as a separate operation. To the sheet thus formed is cemented the flexible sheet 31.

It will be understood that within the scope of the appended claims wide deviations may be 15 made from the forms of the invention described without departing from the spirit thereof.

I claim:

1. A shoe having, in combination, an insole having toe and heel portions comprising sheets 20 of relatively stiff material, a sheet of relatively flexible material having its upper surface substantially continuous with the upper surfaces of said sheets of relatively stiff material and extending from one to the other and including at 25 least the ball portion of the insole, a sheet of relatively flexible rubber impregnated fibrous material secured to the under sides of said relatively stiff sheets and first mentioned sheet of relatively flexible material, and uppers cemented 30 to said rubber impregnated sheet at at least the toe and ball portions of the insole.

2. A shoe according to claim 1 in which the relatively stiff sheets are of relatively hard fiberboard and the rubber impregnated sheet is se- 35 cured by cement to the other sheets.

ARTHUR C. SEWALL.
